UNITED STATES PATENT OFFICE

2,224,220

PARTITION ASSEMBLING MACHINE

Charles G. Dauber, Oshkosh, Wis., assignor to The
Dauber Company, Oshkosh, Wis., a corporation
of Wisconsin

Application June 23, 1939, Serial No. 280,699

3 Claims. (Cl. 93—37)

This invention relates to improvements in corrugated partition assembling machines, and more particularly to machines for assembling corrugated and chip board partitions of the type employed in beverage cartons, glassware cartons, and other types of cartons and containers wherein individual pockets are required.

In United States Patent No. 2,163,923, of which I am a joint patentee, there is disclosed a complete machine for cutting, slotting and assembling paper board partitions to form carton interior or sub-dividers. In the machine of said patent, due to the fact that the paper board material must be bent or extended over and about certain instrumentalities, it is not practical to use corrugated or chip board for the partition forming material as said latter class of material can not be bent.

It is, therefore, a primary object of the present invention to provide a partition assembling machine adapted to assemble sets of pre-formed corrugated or chip board partition strips and which handles the partition strips or material in such a manner that the same are not subjected to any bending or damaging deflection.

A further object of the invention is to provide a complete corrugated or chip board partition assembling machine which includes as a portion of the entire mechanism, a partition strip assembly feeding arrangement of the type covered by my co-pending application, Serial No. 221,902, filed July 29, 1938.

A further object of the invention is to provide a machine of the character described which has adjustable and interchangeable elements to adapt the machine for the successful handling of partitions of various thicknesses.

A further object of the invention is to provide a machine of the character described wherein the mechanism for steppedly advancing or projecting partitions of one group into assembly position is synchronized with the mechanism for advancing the partitions of the other group.

A further object of the invention is to provide a corrugated or chip board partition assembling machine which is of very simple construction, is efficient, economical and automatic in operation, is strong and durable, and is well adapted for the purposes described.

With the above and other objects in view the invention consists of the improved partition assembling machine, and its parts and combinations as set forth in the claims, and all equivalents thereof.

In the accompanying drawings in which the

same reference characters indicate the same parts in all of the views:

Fig. 1 is a front and side perspective view of the improved partition assembling machine;

Fig. 2 is another perspective view of the machine showing the opposite side and the rear thereof;

Fig. 3 is a longitudinal vertical sectional view of the machine and on a larger scale;

Fig. 4 is a fragmentary, detail sectional view taken on line 4—4 of Fig. 3;

Fig. 5 is a detail sectional view taken on line 5—5 of Fig. 4;

Fig. 6 is an enlarged fragmentary plan view of the feeding mechanism for the longitudinal partition strips; and

Fig. 7 is an enlarged fragmentary side view of a portion of the mechanism shown in Fig. 6.

Referring now more particularly to the drawings it will appear that the improved partition assembling machine includes a box-like base or casing 10 having mounted therein and thereon many of the working parts of the machine. The lower portion of the base supports suitable bearing members 11 in which is journaled a main drive shaft 12 of the machine. An outer end portion of said shaft has fast thereon a large pulley wheel 13 connected by a belt 14 with the pulley wheel 15 on the shaft of a variable speed electric motor 16. The motor receives its energy from a conventional source of electric current.

Forwardly of the drive shaft 12 and journaled in the casing, transversely thereof, is a clutch shaft 17. Said clutch shaft is driven from the drive shaft by means of a small pinion 18 fast on the drive shaft which meshes with a large gear 19 carried by a sleeve 23 on one section of the clutch shaft. A movable clutch element 20 is splined to another portion of the shaft 17 and its teeth 21 may be brought into and out of engagement with the teeth 22 of the sleeve 23. The clutch element 20 is moved into and out of clutching position by a fork 24 mounted fast on a longitudinally extending shaft 25. At the forward end of the machine housing said shaft carries a miter gear 26 engaged by a segment gear 27. The segment gear is on a rod 28 which also carries a clutch lever 29. With reference to Fig. 3 when said clutch lever is in the full line position the shaft 25, through the various connections explained, will have been turned to have caused the fork 24 to engage the clutch element 20 with the teeth of the clutch element 23. With the clutch lever in this position, and with the motor 16 in operation, the mechanism for the entire

machine will be in operation. However, if the clutch lever 29 is moved to the broken line position of Fig. 3, the clutch will be disengaged and the machine will idle.

5 It should be noted that the clutch lever rod 28 is mounted in bracket plates 30 carried by the lower forward portion of the housing 10. Also, on the driven portion of the clutch shaft 17 there is a friction brake 31 having a braking strip 32 coiled thereabout. The outer end of the braking strip is carried by a bolt 33 which is adjustably threaded into a wall of the housing 10. Adjustments of the bolt 33 will vary the tension which the strip 32 imposes on the surface of the 10 brake drum 31. The brake is for the purpose of preventing "coasting" of the mechanism. The inner end of the braking strip is anchored to the housing or frame, as at 34 (Fig. 3).

On a reduced end of the clutch shaft 17 (see 20 Figs. 1 and 4) there is a slotted guide block 35 in which is adjustably secured a crank pin 36. Pivotally mounted on one end of the crank pin is a socket member 37 which adjustably receives one end portion of a crank rod 38. Adjustments 25 of the crank pin 36 and rod 38 will vary the amount of reciprocatory movement of said crank rod. The other end of said crank rod is pivotally secured to the lower end of an arm of a bell-crank lever 39, pivotally mounted on a forward 30 side portion of the housing 10, as at 40. Another arm of the bell-crank lever 39 is pivotally connected with one arm of an upper bell-crank lever 41 by a bar 42, while still another arm of the lower bell-crank lever 39 is pivotally connected with 35 the other arm of the upper bell-crank lever 41 by a bar 43. This arrangement is effective to reciprocate a rack bar 44 whose inner end is carried by the bar 43 and whose serrated outer end engages a pinion 45 fast on a forward trans- 40 verse shaft 46. Hence, the shaft 46 is oscillated and the motion of this shaft is effective to operate certain longitudinal partition feeding mechanism, as will hereinafter appear. Said longitudinal partitions, indicated by the numerals 45 47 are pre-formed and are available for assembly with transverse partitions 48 which are fed into assembly positions by the machine and relative to steppedly advanced sets of the partitions 47.

50 With special reference to the heretofore mentioned longitudinal partition feeding mechanism, it will appear that at the forward end of the machine there is a vertically adjustable strip feeding platform 69. The under portion of said platform 55 is provided at its sides, with depending vertical rails 70 slidably received in vertical tracks 71 on the casing. The platform is held in a desired position of vertical adjustment by a screw 72 threaded into a base support 73 and engaging 60 an upper flange 74 on said platform. On said platform 69 there are a plurality of spaced apart slotted strips 75. Against the side of each strip there is mounted in vertical position a partition supporting panel 49 having an outwardly flared 65 wing 49' on its inner end, as well as a slightly outwardly inclined and tapered plate 50 with an out-turned guiding edge 51 at its upper edge. The panels 49 are adapted to support the rear end portions of forwardly advanced pre-formed 70 partitions 47, while the plates 50 receive and support the forward end portions of succeeding partitions. The succeeding partitions may be put into position indiscriminately at any stage of the advancement of the forward partitions, and the 75 inclination of the plates 50, together with the out-

turned edges 51 thereof and the wings 49', permit easy insertion of said latter partitions with their forward ends overlapped by the rear ends of the forward partitions without undue binding and frictional engagement, as best shown in Fig. 6. 5

Slidably mounted within the slot of each strip 75 is an advancing bar 80 of relatively short length. Extending vertically upwardly from the top face of each bar is a pair of spaced apart posts 52 with each post having the hub portion 10 of a laterally extending finger 53 pivotally mounted thereon. The outer end portion of each of said fingers is reduced and angled for entrance into apertures 54 of the pre-formed partitions 47, and the fingers are resiliently edged toward the 15 faces of said partitions by springs. The posts and fingers are so arranged that when the fingers are in engaging positions, the distance between the ends of a pair is equal to the distance between three apertures 54 in a partition. To 20 insure this condition the rear posts 52 may be longitudinally adjustably mounted on their bars. Each slotted strip 75, near its inner end, carries on a suitable bracket a curved band spring 55 to engage a portion of a forward partition and to 25 hold it against the panel 48, and a resiliently mounted pivotal finger 56 for engaging a lower fast portion of a partition.

In order that the bars 80 may be reciprocated, each of the same carries a depending yoke 83 30 which straddles and is moved by a transverse connection 84. The transverse connection is moved forwardly and rearwardly relative to the platform 69, to thereby move the bars 80 in their slotted strips 75 with resulting intermittent advancing movements of the partitions 47 through the medium of the upper transverse rock shaft 46 previously referred to. Said rock shaft has fast thereon a pair of cranks 86 whose end portions are pivotally connected with a suitable portion of 40 the connection 84. Through the mechanism described the advancing bars 80 of the partition feeding platform are intermittently reciprocated forwardly and rearwardly. On movements of said bars toward the machine, the ends of the fingers 45 53 drop into spaced pairs of apertures 54 in the forward partitions 47. After engagement of the same and continued forward movement of the bars the engaged partitions are moved inwardly until the forward limit of movement of said bars 50 is reached, the movement being initially adjusted so as to bring a series of slots in said pre-formed partitions beyond the ends of the panels 49 and into correct assembly position for engagement 55 with a transverse partition 48 being projected downwardly from another portion of the machine. Other specific details of the longitudinal partition feeding mechanism need not here be referred to and it may be stated that said mechanism is fully described in my co-pending application, Serial No. 221,902, filed July 29, 1938. 60

Projecting upwardly from the top forward portion of the housing 10 is a frame 87 which rigidly supports an abutment plate 88. Adjacent the inner face of said plate there is disposed a vertically reciprocable plunger blade 89. The side edges of said blade carry guide lugs 90 which move in vertical slots 91 in the end members of the frame 87.

The mechanism for reciprocating the plunger 70 blade 89 includes the following elements: On one end of the clutch shaft 17 there is mounted fast a crank 92 to whose outer end a connecting rod 93 is pivotally attached by a wrist pin 94. The other end of said connecting rod is pivotally se- 75

cured to a side portion of a segment gear 95 by a wrist pin 96. The segment gear is carried fast by the outer end of a transverse counter shaft 97 journaled in the casing 10. The other end 5 of said counter shaft carries a similar segment gear 98. The upper ends of vertical bars 99 are secured to the opposite side lugs 90 of the plunger blade 89. Said bars 99 depend on opposite sides of the housing 10 and are suitably guided and 10 supported. The lower ends of said bars are formed as racks with the teeth thereof being engaged by the teeth of the segment gears 95 and 98 respectively.

Mounted over the housing 10 and extending 15 rearwardly angularly upwardly is a table 100 having adjustable side rails 101. The forward end of said table terminates adjacent the inner face of the abutment plate 88 and is spaced therefrom an amount slightly greater than the thickness of 20 a transverse partition 48, whereby a vertical slot 102 (see Fig. 3) is provided. By means of bolts 103 and slots 104 in the supporting brackets 105 for said table, said table may be subjected to slight longitudinal adjustments to increase or decrease 25 the width of the slot 102, thereby adapting the mechanism for runs of partitions of different thickness stock.

A group or stack of transverse, pre-formed partitions 48 are placed transversely on the forward 30 end of the table 100 between the side rails 101, the side rails being adjusted for the length of the partitions and engaging the ends of the same. The forward-most partition of the stack engages 35 against the inner face of the abutment plate 88 and does not move downwardly through the slot 102 until it is pushed by the plunger blade 89 inasmuch as friction and pressure imposed by the stack retains it until it is positively pushed downwardly. The partitions 48 of the stack are always 40 maintained in tightly arranged condition with the forward partition against the abutment plate by means of a movable pusher carriage 106. Said carriage is provided with wheels and is disposed on the table 100 rearwardly of the stack of partitions and with its front end abutting against 45 the rear partition of the stack. Depending pins 107 on the carriage extend through and are guided in a longitudinal slot 108 in the table. One end of a cable 109 is secured to one of the pins 50 107 and then extends about a pulley 110 mounted on a lower inner portion of the table. The cable also extends over another pulley 111 depended from an outer portion of the table. A weight 112 is freely suspended from a lower portion of the 55 cable. By this arrangement the carriage is constantly urged forcefully against the stack of partitions and each time a partition at the inner end of the stack is removed, the force exerted by the carriage will cause the next partition to 60 firmly engage the abutment plate 88.

It is of course possible that sometimes transverse partitions may be run which are of a different weight of stock than those previously run. The plunger blade 89 utilized should be of a 65 thickness slightly less than the thickness of a partition 48 in order that it may engage the top edge of only one partition and push it downwardly through the slot 102. For this reason interchangeable blades 89 may be used, the selected blade being of the proper thickness for 70 the stock being run. The blade being utilized is removably secured to the lugs 90.

It is believed that from the foregoing description of the partition assembling machine the 75 operation of the same will be fairly obvious.

However, to summarize, it should be recalled that the motive power for the machine is obtained from the variable speed motor 16, and to set the various instrumentalities into operation the clutch lever 29 should be moved to the full line 5 position of Fig. 3, whereupon the transverse partition feeding mechanism and the longitudinal partition feeding mechanism will both be in operation. A stack of pre-formed transverse partitions are placed in the table 100 in the manner 10 previously described and a set of pre-formed longitudinal partitions are stationed against the supports 48 and 50 on the table 69. As brought out in my copending application, Serial No. 221,902, 15 additional longitudinal partitions must be inserted from time to time in overlapped relation with respect to the longitudinal partitions there-ahead.

When the partitions of both sets are disposed as described and the machine is in operation, the 20 plunger blade 89 will move the foremost partition 48 in the stack downwardly through the slot 102 and engage the slots in said partition with the complementary slots in the set of longitudinal partitions. The longitudinal partition feeding mechanism had previously advanced the longitudinal partitions so that the slots thereof were exactly aligned with the feeding slot 102 through 25 which the transverse partition was projected. Upon engagement of a transverse partition with a 30 set of longitudinal partitions the segment gears 95 and racks 99 become effective to raise the plunger blade 89 and the machine is so synchronized that during the raising of the plunger 35 blade the longitudinal partition feeding mechanism will operate to advance the longitudinal partitions a distance equal to the space between a pair of slots in said partitions. Thereafter the plunger blade 89 is lowered to eject a new transverse partition 48 and to set it into a subsequent 40 set of slots in partitions 47. The machine continues to operate in this fashion and the complete partition assemblies move out of the machine along an inclined guideway 113.

From the foregoing description it will be evident that the improved machine operates automatically and requires little attention from the operator. It feeds and spaces the partitions extremely accurately and the various mechanisms 45 may be minutely adjusted to adapt the machine 50 to work on stock of different weights or thickness. It should be particularly noted that the partitions which are assembled by the machine are not subjected to any bending or deflection and 55 this is important in that it adapts the machine for use in connection with partitions formed of corrugated or chip board. Corrugated or chip board is of such a nature that it cannot be bent without cracking or spoiling the material and the 60 present machine therefore handles this class of material in a very satisfactory manner. The improved machine is of simple and novel construction and is well adapted for the purposes set forth. 65

What is claimed as the invention is:

1. In a machine for assembling pre-formed partition strips, said strips including a set of longitudinal strips and a set of transverse strips and all of the strips having a longitudinal succession 70 of spaced-apart slots therein, a support on which the longitudinal strips are vertically stationed with the slots thereof opening upwardly, said support being arranged to accommodate overlapped portions of adjacent partitions, a slide 75

- member reciprocably mounted relative to the support, resilient means carried by the slide member engageable in successive strip slots upon reciprocations of said slide member in one direction and automatically releasable from said slots and movable longitudinally of a strip upon reciprocations of said slide member in the opposite direction, means for holding a group of forward partition strips in parallel, steppedly advanced positions upon movements of the slide member in the latter direction, means for supporting a stack of transverse partition strips in inverted positions with the slots thereof opening downwardly, and means for intermittently removing the innermost strip in said stack downwardly from said stack and engaging its slots with an advanced series of slots in the first-mentioned group of strips.
2. In a machine for assembling pre-formed partition strips, said strips including a set of longitudinal strips and a set of transverse strips and all of the strips having a longitudinal succession of spaced-apart slots therein, means for longitudinally movably supporting a group of laterally spaced longitudinal strips, said strips being on their lower edges with the slots thereof opening upwardly, means for automatically steppedly advancing the strips of said group without bending or deflection as to planes, a station at which successive transverse partitions are interlocked with advanced slotted portions of the spaced longitudinal strips, a table on which a stack of said transverse partitions are disposed with the slots thereof facing downwardly, a supporting plate adjacent the inner end of the table engaged by the face of the innermost partition of the stack, there being a slot between the inner end

of the table and said plate, a reciprocatory blade movably mounted adjacent said plate and engageable with the edge of an innermost transverse partition of the stack to eject the partition through said slot toward said assembly position, controlled means for automatically reciprocating said member, between advancing movement of the longitudinal strip moving means, and a common drive for the blade reciprocating means and for the longitudinal partition advancing means.

3. In a machine for assembling pre-formed partition strips, said strips including a set of longitudinal strips and a set of transverse strips and all of the strips having a longitudinal succession of spaced apart slots therein, a support on which one set of strips are vertically stationed and with the slots thereof opening upwardly, said support being arranged to accommodate overlapped portions of adjacent partitions, a slide member reciprocably mounted relative to the support, resilient means carried by the slide member engageable in successive strip slots upon reciprocations of said slide member in one direction and automatically releasable from said slots and movable longitudinally of a strip upon reciprocations of said slide member in the opposite direction, means for holding a group of forward partition strips in parallel, steppedly advanced positions upon movements of the slide member in the latter direction, means for supporting a stack of partition strips of another set, and means for intermittently removing the innermost strip in said stack and engaging its slots with an advanced series of slots in the first-mentioned group of strips.

CHARLES G. DAUBER.
